% Hamilton Cosco, Inc., Gallatin, Tenn.

Filed May 18, 1965, Ser. No. 85,337

Term of patent 14 years
(Cl. D15—1)

FIG. 1 is a front elevation of a chair pedestal showing our new design;

FIG. 2 is a plan view thereof;

FIG. 3 is a modified form of the chair of FIG. 1 wherein the casters are omitted and the central sleeve member is elongated; and

FIG. 4 is a plan view of the chair pedestal shown in FIG. 3.

The pedestals shown in FIGS. 1 and 3 have the same appearance when viewed in elevation from any quadrant.

We claim:

The ornamental design for a chair pedestal, as shown and described.
